UNITED STATES PATENT OFFICE.

WILLIAM HENRY SUMBLING, OF TORONTO, ONTARIO, CANADA, ASSIGNOR TO
SUMBLING MACHINERY COMPANY, LIMITED, OF TORONTO, ONTARIO, CANADA.

COMBINED GRINDING-WHEEL GUARD AND REST.

1,386,741.

Specification of Letters Patent. Patented Aug. 9, 1921.

Application filed June 1, 1920. Serial No. 385,455.

To all whom it may concern:

Be it known that I, WILLIAM HENRY SUMBLING, of the city of Toronto, county of York, Province of Ontario, Canada, a subject of the King of Great Britain, have invented certain new and useful Improvements in Combined Grinding-Wheel Guards and Rests, of which the following is a specification.

- 10 My invention relates to improvements in combined grinding-wheel guards and rests, and one object of my invention is to provide a guard designed to support a rest, which guard may be adjusted as the occasion may require to compensate for the wearing away of the grinding wheel, and to so mount the rest on the guard that the rest may be given the desired adjustments thereon, so that when the guard has been adjusted 15 to compensate for the wear of the grinding-wheel, the member against which the work is held may be adjusted so that its upper face or surface may be held in a horizontal plane. A still further object of my invention is to 20 improve the construction of the guard patented to me in the United States on the 24th day of February, 1920, #1,332,009, so that I may be able to use an ordinary standard machine bolt to couple the guard to the 25 frame of the grinder, and otherwise to improve the construction of the said guard. A still further object of my invention is to provide improved clamping or fastening means both for the guard and the rest, so 30 that the user thereof will always have at hand the necessary means for adjusting the guard and rest and locking the same in position.

In the following specification I shall set 35 forth my invention and certain modifications thereof, and what I claim as new will be stated in the claims forming part thereof.

Figure 1 is a plan view of my combined guard and rest, showing the guard attached 40 to the frame of a grinding machine, part of which is shown. Fig. 2 is a side elevation of my combined guard and rest. Fig. 3 is a front elevation of my combined guard and rest, showing the portion of the grinder 45 frame which carries the guard. Fig. 4 is a side elevation of a modified form of the guard. Fig. 5 is a horizontal cross-section on the line 5—5, Fig. 4, and Fig. 6 is a side 50 elevation of a modified form of the bracket 55 carried by the grinder frame which supports the attaching means for the guard.

In my Patents numbered 1,294,565, and 1,332,009, dated respectively Feb. 24, 1920, and Feb. 18, 1919, I show a long slot formed in the plate of the guard, and I have found 60 from experience that if I make two slots in the said plate, one whereby the guard is mounted on the arbor, or boss carried by the frame of the machine, and the other considerably smaller in size through which 65 the fastening means passes, I am enabled to save in weight without sacrificing strength, and yet secure the range of adjustments desired. In fact through my improved construction of the guard, I am not confined to 70 using a slot closed at both ends whereby the plate is mounted over the boss or arbor.

In my first-mentioned patent, means was provided whereby the guard could be moved transversely of the arbor and circumferentially of the wheel, but the rest could not be 75 independently adjusted to the extent of placing the upper surface thereof in a horizontal plane. Where it is required to grind a part of the work to be more or less at right angles to another part thereof, it was found that unless the machinist had a fixed bed or support held with its work-supporting surface in a horizontal plane on which the work could be held, accurate work could not be 80 done. In this present invention the rest can be adjusted so that the work-supporting element will be moved into the horizontal after the guard itself has been given the necessary 85 adjustment. In the present construction I 90 preferably position the slots in the guard plate so that they will extend transversely of the machine, and preferably use a curved slot in the bracket carried by the machine frame through which the fastening means 95 for the guard passes, thereby giving me independent horizontal and circular adjustments of the guard. When the wheel wears considerably, the guard must be adjusted 100 circumferentially thereof so as to reduce the size of the opening above a line passing horizontally through the arbor, which is desirable according to the best practice. This circumferential adjustment necessarily will leave the top face supporting the rest at an 105 angle to the horizontal, and therefore inde-

pendent adjustment of the rest must be had so that the top face thereof may be adjusted into horizontal position.

It must be clearly understood that the opening in the guard plate through which the arbor passes, as well as the opening through which the fastening means passes, need not be slots, but may be openings of such shape as to permit the guard to be mounted and clamped in place so as to provide for the required adjustment of the guard. Since the rest is capable of a considerable horizontal adjustment, the horizontal adjustment so obtained may, in some cases, render unnecessary the horizontal and circumferential adjustment of the guard. In the drawings, like characters of reference refer to the same parts.

The grinder frame used to illustrate my invention therewith may comprise any suitable frame A, a portion of which only is shown, and journaled therein is an arbor C to which is attached, in any suitable way, the grinding wheel D shown by dotted lines 25 in Fig. 2

Secured to, or formed a part of, the frame A is a bracket E. The guard comprises a plate 3 which supports a flange 4 within which rotates the grinding wheel D. The 30 flange 4 is cut away as shown at 5 to permit the work to be brought into contact with the wheel D. Formed centrally in the plate 3 is an opening 6, preferably in the form of a slot which extends transversely of the machine. It will be seen upon referring particularly to Fig. 2 that the arbor C passes through said slot. To prevent the sides of the slot 6 coming in contact with the arbor C, I prefer to provide the frame A with a 40 boss B which extends preferably through to the inner side of the plate 3. Though I do not confine myself to using the said boss, I prefer to use the same because I can keep the plate 3 out of contact with the said arbor.

Since the opening 6 will be cast in the plate 3 so that it may be readily mounted over the boss B, I do not have to machine said opening, and therefore I can reduce cost of manufacture. 7 is a slot preferably curved and formed in the bracket E, and extending through this slot is an ordinary machine bolt 8. F is an opening preferably in the form of a slot, formed in the plate 3 and communicating with the slot 7 and through this slot F extends the bolt 8. As will be seen clearly in Fig. 1, the slot F is preferably counter sunk so as to form a housing for the head 9 of the bolt 8. The size of 50 this head is such that it will contact with the walls 10 of the slot F, consequently the rotation of the bolt 8 will be prevented. The bolt 8 is threaded as shown at 11 and screwing thereon is a nut 12 provided with a head 13 in the form of a cross bar. This

nut and its head will always be carried by the bolt 8, and without further description it will be understood that the co-action between said nut and bolt mounted substantially in the manner shown will firmly lock 70 the guard in adjusted position. Since the guard through the medium of its plate 3 rests in contact either with the boss B or the arbor C, pressure against the rest will not shift the guard.

Since I prefer to use the slot F, the same is formed to extend transversely of the machine frame, and it will be understood that by retracting the nut 12 the guard can be loosened and adjusted horizontally.

If I use an opening in the form of curved slot 7, by retracting the nut 12 the guard can be adjusted circumferentially of the wheel D, for the purpose before set forth.

Secured to, or formed a part of, the 85 guard, is a bracket 14 provided with a longitudinal slot 15 opening therethrough. The said slot is constructed to provide shoulders 16 which form flanges against which rests the head 17 of the bolt 18. The said head 17 is countersunk in the bracket 14 and rests in the said slot 15, and since the sides of this head contact with the walls 19 of the slot 15, the bolt is prevented from turning. The said bolt is threaded to receive the nut 20 which is provided with a head 21 in the form of an arm. The parts described functionate in like manner to the clamping means already described in connection with the guard itself. Formed in the arm 22 of the bracket 23 is a vertical slot 24 through which extends the bolt 18. Upon referring particularly to Fig. 3 the parts just described, it will be seen, clamp the bracket 23 to the bracket 14, and without further description it will be understood that the bracket 23 can be adjusted vertically and around the bolt 18.

The arm 25 of the bracket 23 occupies substantially a horizontal plane, and extends in front of the wheel D. 26 is a rest, and the same is provided with a threaded bolt 27 which extends through a longitudinal slot 28 formed in the arm 25, and screws into the nut 29 constructed substantially the same as the nuts 12 and 20 already described.

By reason of the slot 15 the bracket 23 may be adjusted horizontally in respect of the wheel D, and by means of the slot 28 the rest 26 may be adjusted transversely of the wheel D, or otherwise.

Sufficient has been shown to support the claim that I may dispense with the use of the openings formed in the plate 3 in the form of slots, in some cases because of the range of adjustments possessed by the bracket 23 and rest 26, though the use of the said slots is preferred because of the wider range of adjustment to be had therewith.

As before mentioned I lighten the construction of the plate 3 by forming two separate openings therein, for example the slots 6 and F. The metal separating these slots 5 may be termed a bridge wall 30, and it is this portion of the said plate 3 that stiffens the same.

In Fig. 4 I show the opening or slot 6' as having only one closed end, and have otherwise modified the shape of the plate 3. This modification enables me to manipulate to advantage certain classes of work. The bracket E' shown in Fig. 6 has a modified opening 7' in the form of a round hole 15 through which passes the bolt 8.

In order to make the plate 3 in the modified form shown in Fig. 4 I cast therewith a strengthening rib a, so as to give added strength to the bridge wall 30.

Obviously various changes in details of construction may be suggested by one skilled in the art without going outside the scope of the appended claims.

What I claim is:

1. In a grinding machine, the combination with a grinding wheel journaled therein, of a guard for said wheel having a plate provided with an opening centrally thereof through which extends the arbor of said wheel; means coupled to the frame of said machine and adapted to co-act with said plate to permit said guard to be moved transversely of said machine and circumferentially of said wheel and designed to firmly support said guard in adjusted position; a slotted bracket carried by said guard at one side and projecting forwardly thereof and disposed substantially in a vertical plane, and means adjustably carried by said last-mentioned bracket and adapted to be adjusted to provide a horizontal rest for the work when the adjustment of said guard renders this adjustment necessary.

2. In a grinding machine the combination of a standard having a projecting boss; a slotted bracket carried by said standard; a guard having a plate provided with two slots opening therethrough, which are spaced apart, one of said slots being adapted to receive said boss and positioned to extend through the axis of said plate; the other slot being positioned to the rear of the first-mentioned slot and somewhat below the same; fastening means held in said slotted bracket and in the second-mentioned slot formed in said plate to clamp said plate firmly to said bracket; a slotted bracket carried by said guard at one side and pro-

jecting forwardly thereof and disposed in substantially a vertical plane, and a tool rest adjustably carried by said last-mentioned bracket and adapted to be adjusted into horizontal position when the adjustment of said guard makes this adjustment necessary.

3. In a grinding machine, the combination with a grinding wheel journaled therein, of a guard for said wheel having a plate provided with an opening centrally thereof through which extends the arbor of said wheel; means coupled to the frame of said machine and adapted to co-act with said plate to permit said guard to be moved transversely of said machine and circumferentially of said wheel and designed to firmly support said guard in adjusted position; a slotted bracket carried by said guard at one side and projecting forwardly thereof and disposed substantially in a vertical plane; a rest comprising a right angle bracket provided with a longitudinal slot in the vertical and horizontal members thereof; fastening means held in the slotted bracket carried by said guard and extending through the vertical slot formed in said right-angle bracket; the combination set forth permitting vertical horizontal and circular adjustment of said right angle bracket; a tool rest supported by said right angle bracket on the horizontal member thereof, and fastening means coupling said tool rest to said horizontal member and whereby said tool rest may be adjusted thereon.

4. As a new article of manufacture, a guard having a plate provided with two openings therethrough, which are spaced apart, one of said openings being of greater diameter than the other and positioned to extend through the axis of said plate; and a slotted bracket carried by said guard at one side and projecting forwardly thereof and disposed in substantially a vertical plane.

5. As a new article of manufacture, a guard having a plate provided with two slots opening therethrough, which are spaced apart, one of said slots being of greater diameter than the other and positioned to extend through the axis of said plate; the other slot being positioned to the rear of the first-mentioned slot and somewhat below the same; and a slotted bracket carried by said guard at one side and projecting forwardly thereof and disposed in substantially a vertical plane.

WILLIAM HENRY SUMBLING.
